CLAIM

I claim the ornamental design for a cutting channel of a cigar cutter, as shown and described.

DESCRIPTION

FIG. 1 is a rear side perspective view of a cutting channel of a cigar cutter, showing my new design;

FIG. 2 is a front side perspective view thereof;

FIG. 3 is a front elevation view with the cutting blades fully retracted; and,

FIG. 4 is a front elevation view with the cutting blades partially retracted.

The broken lines disclosures of the cigar and cigar cutter are shown for illustrative purposes only and form no part of the claimed design.
